to M. Seller Company, San Francisco, Calif., a corporation of Oregon

Application April 15, 1938, Serial No. 76,547

Term of patent 7 years

To all whom it may concern:

Be it known that I, Edward C. Styskel, a citizen of the United States, residing at San Francisco, in the county of San Francisco, State of California, have invented a certain new, original, and ornamental Design for a Plate or Similar Article, of which the following is a specification, reference being had to the accompanying drawing forming a part thereof.

Figure 1 is a top plan view of a plate embodying
my new design.

I claim:

The ornamental design for a plate or similar article, as shown.

E. C. STYSKEL.
